(57) **CLAIM**

I claim the ornamental design for an oil filter change device, as shown and described.

DESCRIPTION

FIG. 1 is a perspective view of the design for an oil filter change device;

FIG. 2 is a top view of the design of FIG. 1;

FIG. 3 is a bottom view of the design of FIG. 1;

FIG. 4 is a left side view of the design of FIG. 1;

FIG. 5 is a rear side view of the design of FIG. 1;

FIG. 6 is a right side view of the design of FIG. 1; and,

FIG. 7 is a front side view of the design of FIG. 1.

The broken lines are shown for illustrative purposes only, including environmental configuration, and form no part of the claimed design.

1 Claim, 7 Drawing Sheets
